UNITED STATES PATENT OFFICE.

JAMES A. MCNAUGHTON, OF NEW YORK, N. Y., ASSIGNOR OF ONE-HALF TO GEORGE PLUSKAT, OF BROOKLYN, NEW YORK.

TABLE ATTACHMENT.

1,072,248.

Specification of Letters Patent.

Patented Sept. 2, 1913.

Application filed August 27, 1912. Serial No. 717,279.

To all whom it may concern:

Be it known that I, JAMES A. MCNAUGHTON, a citizen of the United States, and a resident of the city of New York, borough 5 of Brooklyn, in the county of Kings and State of New York, have invented a new and Improved Table Attachment, of which the following is a full, clear, and exact description.

10 This invention relates generally to table attachments, and is more particularly directed to an improved structure adapted to hold vessels or receptacles containing food at different heights from the table.

15 The principal object of the invention is to provide a new and improved attachment of the class described which may be disposed of at small cost due to the simple construction rendering the production thereof possible at 20 a low figure.

Further objects and advantages of the invention will be disclosed as the description thereof proceeds.

Reference is to be had to the accompanying drawings forming a part of this specification, in which like characters of reference denote corresponding parts in both the views, and in which—

Figure 1 is a perspective view of one form 30 of the attachment; while Fig. 2 is a partial perspective of a modification.

Referring particularly to Fig. 1, the device comprises the fixed and spaced uprights 1 provided with a number of spring-pressed 35 stops 2 thereon, the lower end of the uprights being integral with offset portions 3 adapted to lie adjacent the top of the table, there being a U-shaped portion 4 positioned beneath the table and connected with the 40 said portions 3 by means of vertically extending parts 5. The structure so far described is designed to be attached to the table by engagement with opposite sides of the top, the element which supports the vessel or 45 dish being adjustably mounted on this supporting frame in a manner to be now described.

The vessel or dish is designed to be received in a frame 6 which may be made of 50 bent wire, if so desired, or short lengths of tubing, substantially dished and circular in formation, and having downwardly extending posts 7 adapted to come adjacent the said uprights 1; the posts are spaced and held relatively to each other by means of

cross pieces 8 secured thereon, the ends of the lower cross pieces being extended and provided with openings 9 through which the said uprights 1 pass, the frame being then bodily movable longitudinally of the uprights, the said stops 2 forming rests for supporting the frame. The top cross piece 8 is rigidly secured in any suitable manner to the posts 7.

The top cross piece 8 is preferably provided with a catch 10 having a bent lower end 11 adapted to engage either of the lower cross pieces 8 in order to maintain the frame 6 at different elevations with respect to the lower cross pieces, as indicated in the drawings. If so desired, one of the cross pieces may be provided with a holder 12 adapted to support a spoon 13.

In order to more firmly secure the attachment on the table and prevent slipping, a resilient structure may be employed comprising a U-shaped frame 14 of springy material, positioned on the said parts 5 of the supporting member and movable therealong, being held in certain position through the medium of helical springs 15. In order to hold the table-cloth immovable on the table, and thereby prevent pulling of the cloth, disturbing the attachment, the under part of the supporting frame 4 may be provided with an opening receiving a threaded and sharp-pointed screw 16 adapted to engage the cloth on the under side of the table.

In Fig. 2 a slight modification is shown which embodies a framework made up of 90 the ends 17 and the sides 18, together with the cross pieces 19, preferably provided with a forwardly extending part 20. As far as the result following the use of this modification is concerned, no substantial advantage 95 is apparent over that shown in Fig. 1, the construction due to the frame-like arrangement of the parts 17, 18 and 19, however, presenting a more substantial and rigid structure.

In the use of the device the U-shaped frame 4 is positioned beneath the table top, while the U-frame 14, together with the offset portions 3, are positioned adjacent the upper side of the table, the parts being brought into such position by being forced inwardly thereon; the frame 6 may be moved up or down relatively to the lower cross pieces 8 because of the openings in the ends of the cross pieces which engage the posts 7, 110

the parts being held in such position by bringing the bent lower end 11 of the catch 10 into engagement with these lower cross pieces. The frame 6, along with the cross pieces, is also adjustable longitudinally of the uprights 1, being held at different elevations by means of the spring-pressed stops 2, these stops yielding when the ends of the cross pieces are moved adjacent the stops. 10 Any desired receptacle or vessel may be placed within the frame 6, after which it may be brought to the desired elevation by manipulation of the parts as described.

It will be apparent that the size and shape, 15 as well as the particular materials used in the production of the attachment may be varied in order to produce an article adapted to support vessels or dishes of various sizes, such changes being comprehended within 20 the inventive idea disclosed.

Having thus described my invention, what I claim as new and desire to secure by Letters Patent is:—

25 1. An article of the class described comprising spaced uprights adapted to be carried adjacent the table top, resilient means engaging the top for holding the uprights in position, a frame, posts extending from the frame, cross pieces engaging the posts and uprights, a cross piece secured to the posts, and a catch carried by the last-mentioned cross piece adapted to engage the others, whereby the frame may be held at different 30 heights above the table.

35 2. A table attachment comprising spaced uprights, means whereby they may be held in position adjacent the table top, a frame adapted to hold a dish or vessel, posts car-

ried by the frame, cross pieces engaging the posts and uprights, the parts being movable relatively one to the other, a cross piece secured to the posts, and a catch carried by the said last cross piece and adapted to engage one of the first-mentioned cross pieces, whereby the frame may be held at different 45 elevations above the table, the said uprights being provided with spring-pressed catches whereby the uprights and frame may be moved longitudinally of the said uprights.

3. A table attachment, comprising spaced 50 uprights adapted to be held in position adjacent the table top, a frame adapted to hold a dish or vessel, posts carried by the frame, extending downwardly therefrom and lying adjacent the said uprights, cross pieces carried by the posts and uprights, the posts and uprights being movable relatively to the cross pieces, a cross piece fixed to the posts, a catch carried by the said fixed cross piece and adapted to engage in one of the other 55 cross pieces, whereby the position of the frame and posts relatively to the first-mentioned cross pieces may be varied, and catches carried by the uprights for engagement with the said first-mentioned cross 60 pieces, whereby the said frame and cross pieces may occupy different positions relatively to the said uprights.

In testimony whereof I have signed my name to this specification in the presence of 70 two subscribing witnesses.

JAMES A. MCNAUGHTON.
